CATHODE-RAY ULTRA HIGH FREQUENCY
RECEIVER

Arthur R. Knight, Dayton, Ohio

Application November 23, 1942, Serial No. 466,973

11 Claims. (Cl. 250—27)

(Granted under the act of March 3, 1883, as
amended April 30, 1928; 370 O. G. 757)

1

The invention described herein may be manufactured and used by or for the Government for governmental purposes, without the payment to me of any royalty thereon.

My invention relates to radio receiving systems and more particularly to a self-contained receiver utilizing cathode ray tube principles.

An object of this invention is to provide a radio wave detecting device for ultra high frequencies of the order of 10 centimeters wave length or less.

Another object is to provide a self-contained wave detecting device in which a cathode ray beam is made to sweep across the radio frequency field of the receiving antenna and indications are derived from a photosensitive mosaic plate.

Another object is to provide a new means of modulation detection employing a rectifier in the amplified output of the mosaic plate.

In the drawings:

Fig. 1 is a conventional schematic side view of a cathode ray tube of the iconoscope type with the principle of my invention incorporated therein.

Fig. 2 is a cross-sectional view of the tube taken through the deflecting plates of Figure 1.

Fig. 3 is a graph showing the distribution of voltage along a half-wave antenna at resonant frequency.

Fig. 4 shows the resultant voltage output of a receiving tube operating in accordance with the principles of the invention.

Referring now in greater detail to the drawings, Fig. 1 shows a cathode ray tube 11 of the iconoscope type comprising the usual cathode 12, with heater 13, control grids 14, deflecting plates 15 and 20, mosaic 16, and signal plate of which the terminal 7 is shown and from which the output voltage is obtained across the load resistor 18. This invention contemplates the use of a single wire or dipole antenna 17, preferably half wave length, resonant to the frequency desired to be received. It may be supported within the tube, as by insulator 19, perpendicular to the axis of the tube 21, 22 and positioned between the mosaic plate 16 and the deflecting plates 15 and 20 as shown at XY, Figures 1 and 2. For longer wave lengths the antenna dipole may extend through the glass but preferably the dipole is cut at its mid-point and fed by a transmission line passing through the glass and excited by an external an-

2

tenna suitable for the wave length to be received.

The electron scanning beam is formed in the usual manner by electrons emitted from cathode 12; accelerated by a source of potential 23; focused by electrodes 14, shown schematically, and directed along the tube axis 21, 22 toward the center of the mosaic screen 16. The beam is positioned horizontally and vertically by scanning potentials applied to the horizontal and vertical deflecting plates 15 and 20 respectively. The scanning potentials are developed by horizontal and vertical deflection generators well known in the art, indicated by blocks 24 and 25.

The light sensitive mosaic plate 16 may be of a type commonly used in television in which a mica sheet is coated with minute globules of photosensitized silver insulated from each other and from an electrically conducting film of metal or graphite on the reverse side. The mosaic is illuminated as by a light source 28 and lens 29. Photoelectric emission causes each globule to emit electrons and thus become a positively charged condenser element with respect to the conducting film on the opposite side of the mica sheet. As the electron scanning beam sweeps across the mosaic, the charged globules are progressively discharged giving rise to a constant current through resistor 18, the voltage drop across which forms the input to amplifier 26.

If now the tube 11 is placed in the radiation field of the desired radio frequency, a standing wave voltage will appear on the antenna 17 in the well known distribution illustrated roughly in Fig. 3, in which the greatest intensity of one polarity is at the top end with the greatest intensity of the opposite polarity at the lower end, and with zero at the center. A somewhat similar potential distribution is of course present when antenna 17 within the tube is electrically excited by another source of resonant frequency such as an external antenna array mentioned previously as more suitable for the longer wave length.

The standing wave which appears on antenna 17, will influence the passing electron stream in its path to the mosaic. Assuming the polarity of the potential at the top of the antenna 17 to be positive and that at the bottom end to be negative, then as the electron beam approaches the antenna 17 at the top of the vertical sweep, it will be attracted to the positive potential there exist-

ing and the flow of electrons to the mosaic will be interrupted until the horizontal sweep carries the beam beyond the range of influence of the potential on the other side of antenna 17. This action will take place on each successive horizontal sweep, but as the beam is carried downward on the vertical sweep, the amount of influence exerted on the stream will decrease proportionately to the potential of the standing wave on antenna 17.

As the beam in its vertical sweep passes the midpoint of antenna 17, however, it is again influenced, this time in a different way. The standing wave now has negative potential with the result that the electrons are repelled as the beam approaches the vicinity of the antenna 17 on its horizontal sweep. Again therefore, the electron flow to the mosaic is interrupted. As the vertical sweep continues this negative influence will increase to the maximum point at the bottom end of antenna 17.

The proportionate amount of influence exerted with the resultant interruption of electron stream flow to the mosaic 16, is illustrated by the diagram AB—RS plotted on the mosaic, in which A—B represents the passage of the beam across the top of antenna 17 and R—S represents passage across the bottom.

With each interruption of electron flow to the mosaic there is a resultant drop in potential across load resistor 18. This is due to the fact that the globules on mosaic 16 lying in the shadow of interruption of the electron stream, are not discharged. This discharge of each globule is the source of potential across resistor 18, and its operation in a cathode ray tube of the iconoscope type is well known to those skilled in the art.

The resultant variation in potential across resistor 18 is illustrated in Fig. 4 in which A—B, represents the potential during the passage of the electron beam across the top of antenna 17, and R—S represents the passage of the beam across the bottom end. The potential across resistor 18 is amplified in the well known manner by amplifier 26.

For some applications it is not necessary or desirable to scan the antenna vertically as described in the foregoing. When the horizontal scanning alone is retained, the vertical deflecting plates may be excited with a constant potential sufficient to hold the scanning beam on the line A'—A—B—B' at the end of the antenna to get the benefit of maximum antenna potential. In this case the square wave output differs from that shown in Fig. 5 in that the waves repeat exactly for constant antenna excitation. If now the radio frequency wave being received is amplitude modulated, the length interrupted, or blank section A—B, will increase and decrease with the amplitude of the modulating wave. This varies the ratio of the blank section A—B to the full sweep A'—B'. If the output of the amplifier 26 is rectified, the value of the rectified current will vary with the amplitude of the modulated wave. Thus in this case the indicator 27 may be a rectifier and a pair of ear phones or a loud speaker. The indicator may also be a cathode ray tube which shows on its face the character of the wave being received. Thus the indicator may be varied to suit the purpose intended.

Having described my invention, what I claim is:

1. A device for detecting radio waves com-

prising antenna means for receiving the waves and setting up a non-uniform field due thereto, means for projecting a stream of electrons through said field, means for setting up a field independent of the first-recited field which acts on said stream for moving the stream in the first-named field, and means for detecting any change in the electron stream due to change in uniformity of the first-named field.

2. The method of detecting radio waves which includes exciting an antenna by the radio waves to be detected scanning the field region of the antenna with a stream of electrons, and indicating variations in the scanning beam due to the field of the antenna by an indicator responsive to light and the electron scanning beam.

3. A radio frequency detector comprising an electron gun for projecting a stream of electrons, an antenna positioned in front of the gun, horizontal and vertical deflecting plates and means for applying sweep voltages to these plates to scan the entire antenna field region line by line from top to bottom, a light sensitive mosaic, a signal plate receiving charge from the mosaic, means placing a uniform light on the mosaic, and means for amplifying and detecting variations in charge appearing on the signal plate.

4. A radio frequency device comprising an antenna excited by radio waves being received so that standing waves appear on the same and a source of electrons accelerated and focused in a beam scanning the antenna field region and subject to variations during scanning due to voltage set up on the antenna a photo and electron sensitive mosaic plate, a light source to illuminate the plate, and means for amplifying and detecting variations in charge on said mosaic plate.

5. A radio frequency device comprising an electron gun, means for giving a scanning action to the electron stream coming from the gun, means, including an antenna located in the area scanned and excited by radio waves being received, for effecting variations in the electron stream a photo and electron sensitive mosaic plate, a light source to illuminate the plate, and means for amplifying and detecting variations in charge on said mosaic plate.

6. A cathode ray tube comprising an electron beam generator, deflecting means for control of said beam, a light sensitive mosaic upon which said beam impinges means responsive to the charges on said mosaic, and an antenna element sensitive to wave radiation mounted therein, so as to be in the scanning path of, and influence the flow of, said beam, a light sensitive mosaic plate, a light source to illuminate the plate, and means for amplifying and detecting variations in charge on said mosaic plate.

7. In a radio receiving system, a cathode ray tube comprising an electron beam generating device, deflecting means for control of said beam, a light sensitive mosaic plate a light source to illuminate the plate upon which said beam impinges, means responsive to the charges on said mosaic an antenna resonant to the frequency desired to be received, positioned in the path of said beam, whereby the voltage on said antenna influences the flow of said beam, and means for amplifying and detecting variations in charge on said mosaic plate.

8. A cathode ray tube of the type utilizing a light sensitive mosaic, signal producing means responsive to the charges on said mosaic a half wave length antenna resonant to a desired radio frequency mounted therein, and so placed as to

have its field completely scanned by the electron beam scanning said mosaic of said tube, a light source to illuminate the mosaic and means for amplifying and detecting charge variations on said mosaic.

9. A device for detecting radio waves comprising antenna means for establishing a non-uniform field within a vacuum enclosure in response to reception of the waves to be detected, an electron gun directing a stream of electrons through said field, scanning means for varying the direction of said stream of electrons before the electrons reach said non-uniform field to scan said non-uniform field, and mosaic means positioned to intercept said stream of electrons after it has passed said first-named means for detecting variations in the stream.

10. A detector of radio waves comprising antenna means for establishing a non-uniform field derived from the waves to be detected, means for

scanning said field with a beam of electrons, and mosaic means for detecting variations in the beam after it has passed through said field.

5 11. The device of claim 10 in which said first-named means is so dimensioned as to effect standing waves thereon to produce said non-uniform field.
